UNITED STATES PATENT OFFICE.

WILLIAM G. KENDALL, OF NEWARK, NEW JERSEY.

VANITY CASE.

Application filed June 26, 1926. Serial No. 118,759.

This invention relates to vanity cases and has for an object to provide an improved case wherein a compact is normally held against removal but so associated with an 5 ejecting device that the compact may be released and ejected with ease.

Another object of the invention is to provide in a vanity case an ejecting device associated with the catch, the arrangement being 10 such that an exaggerated operation of the catch structure will also operate the ejector.

A still further object, more specifically, is to provide a compact ejector for vanity cases wherein an inclined member or cam is used 15 for prying the compact away from its clamping means so that it may be easily removed.

In the accompanying drawing—

Figure 1 is a perspective view of a vanity case disclosing an embodiment of the invention.

Figure 2 is a sectional view through Figure 1, approximately on line 2—2, the same being on an enlarged scale.

Figure 3 is a fragmentary sectional view 25 through Figure 2 on line 3—3.

Figure 4 is a sectional view through Figure 2 on line 4—4, the same being on a slightly reduced scale.

Figure 5 is a perspective view of a catch, 30 ejector and associated parts embodying certain features of the invention.

Figure 6 is a perspective view of a compact holder.

Referring to the accompanying drawing 35 by numerals, 1 indicates the body of a vanity case and 2 the lid connected to the body by a suitable hinge 3. Arranged in the body 1 is a compact holder 4 having resilient members 5 and 6 which pinch to a certain extent the compact plate 7. Arranged preferably diametrically opposite the hinge 3 is a catch 8 which is preferably formed integral with a flat spring 9 riveted or otherwise secured at 10 to the upstanding wall 45 of body 1. In addition to having the catch member 8 co-acting with a suitable member formed on lid 2, the end of the spring 9 is stamped or pressed out for forming a thumb member or button 11. If desired, 50 the button or pin 11 could be riveted in place, though ordinarily, the integral structure is better and also less expensive. The spring 9 is also provided with an integral extension which is bent for forming a hori-

zontal section 12, an inclined or cam section 55 13 and a vertical or supporting section 14, the lower end of the supporting section 14 resting on the horizontal section 12. This structure is preferable, but if desired, a triangular-shaped member or other shaped cam 60 might be soldered, riveted or otherwise secured in place so that it will function in the same manner as the structure shown in Figure 5. This device functions as an ejector and there is a sufficient loose motion to permit the button 11 to be pressed for releasing the cap 2 but if the button 11 is pressed inwardly as far as possible or until it is substantially flush with the outer surface of body 1, the ejector will function and the 65 cam or inclined surface 13 will move beneath the edge of plate 7 and raise plate 7 until it is disconnected from the holder 4. After the button 11 has been released, 70 it will automatically move back to the position shown in Figure 2 and a new compact may be applied and plate 7 pressed until it snaps into the grooves 15 and 16 formed at the juncture of members 5 and 6 with the body of the holder 4.

What I claim is:

1. In a vanity case provided with a compact plate means for holding the plate in position, a catch, a spring having a free end for holding said catch in operative position, and a cam carried by the free end of said spring and positioned to disconnect said plate from said holder when said spring has been moved a predetermined distance.

2. In a vanity case a catch provided with a flat spring, means for clamping one end of said spring rigidly in position, and a radially movable cam arranged at the free end of the catch acting as a compact ejector when the catch has been moved a predetermined distance.

3. In a vanity case a catch provided with a flat spring, and a strip of metal extending from said spring and folded back upon itself for presenting an inclined cam adapted to act as a compact ejector when the spring has been moved to a certain extent in one direction.

4. In a vanity case a catch resiliently held in a given position, and means formed integral therewith presenting an inclined cam surface acting as a compact ejector.

WILLIAM G. KENDALL.
